UNITED STATES PATENT OFFICE.

JAMES A. REASONER, OF ATHENS, OHIO.

TANK CAP.

Application filed April 22, 1922. Serial No. 555,966.

To all whom it may concern:

Be it known that I, JAMES A. REASONER, a citizen of the United States, residing at Athens, in the county of Athens and State 6 of Ohio, have invented certain new and useful Improvements in a Tank Cap, of which the following is a specification.

The present invention relates to a tank cap especially useful upon gasoline or fuel 10 tanks used upon automobiles and other like vehicles and has for its principal object to provide a cap which may be locked against unauthorized removal so that the contents of the tank to which the cap is attached may 15 not be removed or replenished.

Another important object of the invention is to provide a cap of this nature including a safety valve so that the cap will normally be closed except when liquid is 20 actually being poured therethrough thus eliminating the danger of explosions and at the same time preventing dust or undesirable particles from passing through the cap.

25 A further object of the invention is to provide a cap of this nature which will be extremely simple and efficient in construction, reliable in operation, inexpensive to manufacture, durable, and well adapted to the 30 purpose for which it is designed.

With the above and numerous other objects in view as will appear as the description progresses, the invention resides in certain novel features of construction, and the 35 combination and arrangement of parts as will be hereinafter more fully described and claimed.

In the drawing:—

40 Figure 1 is a top plan view of the cap embodying my invention showing the same positioned on a portion of a tank,

Figure 2 is a section taken therethrough substantially on the line 2—2 of Figure 1 looking in the direction of the arrow,

45 Figure 3 is a bottom plan of the cap, and

Figure 4 is a detailed section taken substantially on the line 4—4 of Figure 1 looking in the direction of the arrow.

Referring to the drawing in detail it will 50 be seen that a portion of a tank 1 has been disclosed which is provided with the usual threaded opening 2 for receiving a plug cap. My improved cap consists of a circular body portion 3 having an interior annular 55 groove 4 and a reduced threaded portion 5 the interior of which is curved so as to be

thicker intermediate its ends thereby forming a seat for the removable cap 6 and the hinged valve plate 7. A recess 8 is provided interiorly of the reduced portion 5 for receiving a pin 9 to which is hinged the valve plate 7 which is normally held in a closed position by the U-shaped spring 10 the terminals of which terminate in coils 11 that are wrapped about this hinged pin 9.

60 A bolt 12 extends centrally through the removable cap and supports a spring retaining element 13 which extends diametrically across the cap and has its terminals curved so as to normally seat within the groove 3 70 as is indicated to advantage in Figure 2. A coil eye 14 is provided in this retaining element between one of its terminals and its mid portion so that it may be lifted and the end disengaged from the groove 4 when it 75 is desired to remove the cap. The intermediate portion of this retaining element is coiled about the bolt 12.

An enlargement 17 is formed on the 80 curved periphery of the body 3 and houses a lock indicated at 18 which lock is provided with an inwardly extending bolt 19 and an outwardly extending bolt 20. The outwardly extending bolt 20 is adapted to engage a keeper 21 on the tank 1 while the inwardly extending bolt 19 is adapted to project through the groove 4 and engage over top the removable cap 6 thereby preventing 85 unauthorized removal thereof from its seat in the body 3.

90 On the upper side of the body 3 I have arranged a plurality of projections 23 so that the cap may be easily screwed and unscrewed in and out of engagement with the tank when desired and of course this can only be 95 done when the lock 18 is actuated so as to withdraw the outer bolt 20. The bolts 19 and 20 may be constructed with a lock so as to be actuated simultaneously or separately as may be desired and no particular claim is 100 made to the peculiar structure of the lock since numerous locks now on the market may be readily adapted to this purpose.

105 From the description as it has thus far progressed it will be readily appreciated that in order to fill the tank with a fluid it will first be necessary to remove the removable cap 6 by actuating the lock 18 so as to remove the inner bolt 19. The cap 6 may now be readily removed by disengaging the 110 spring retaining element 13 in the manner previously indicated. The advantage of

this spring retaining element is that should the authorized person fail to actuate the lock 18 so that the bolt 19 would engage the removable cap it would readily be held from 5 accidental replacement by this spring retaining element. After the removable cap has been disengaged from its seat and entirely removed, liquid may now readily be poured through the cap since the weight of 10 the liquid will be sufficient to press downwardly upon the valve plate 7 thus allowing the liquid to readily flow into the tank. This spring 10, however, will close the valve plate 7 immediately upon the flow of liquid 15 ceasing so as to prevent dust or other undesirable particles from blowing through the cap and it will also prevent a flame or a burning match or hot ashes from being dropped into the tank by careless or 20 thoughtless persons. I have provided both the removable cap 6 and the valve plate 7 with suitable vents 24 and 25 so that the liquid in the tank may readily flow therefrom to authorized channels.

25 Although I have described my cap with some degree of particularity, it is to be readily appreciated that this structure has merely been disclosed by way of example and that numerous changes in construction, 30 and in the combination and arrangement of parts may be resorted to without departing

from the scope of the invention as herein-after claimed.

Having thus described my invention what I claim as new is:—

35 1. A tank cap of the class described comprising a body portion of circular formation and having an internal groove, a reduced threaded portion on the body, a bulge provided on the interior of the reduced threaded portion, a valve hinged in the reduced portion so as to normally seat on said bulge, means for holding the valve in a closed position, a removable cap seatable on said bulge, and means for holding the cap in engagement with the bulge, said means comprising a spring element having its intermediate portion attached to the cap and its terminal engageable with said groove.

40 2. A tank cap of the class described including a body portion having means so that the same may be removably attached to a tank, a valve in the body portion means for normally holding the valve closed, a removable cap associated with the body portions, 45 spring means for holding the cap in the body portion and preventing accidental displacement thereof, and positive locking means for preventing displacement of the body portion and also the cap.

50 In testimony whereof I affix my signature.
55 JAMES A. REASONER.
